UNITED STATES PATENT OFFICE.

WILLIAM S. HALSEY, OF BRIDGEPORT, CONNECTICUT.

STEAM-ENGINE.

SPECIFICATION forming part of Letters Patent No. 359,926, dated March 22, 1887.

Application filed September 24, 1886. Serial No. 214,118. (No model).

To all whom it may concern:

Be it known that I, WILLIAM S. HALSEY, a citizen of the United States, residing at Bridgeport, in the county of Fairfield and State of Connecticut, have invented certain new and useful Improvements in Steam-Engines; and I do hereby declare the following to be a full, clear, and exact description of the invention, such as will enable others skilled in the art to which it appertains to make and use the same.

My invention relates to the class of engines known as "liberating cut-off," and has for its object to so simplify and improve the construction and arrangement of the parts which control the taking and exhausting of steam that I am enabled, first, to use two valves only, thus dispensing with two valves heretofore deemed indispensable in this class of engines—that is to say, instead of taking steam by two valves and exhausting by two independent valves, I use but two valves, each of which both takes and exhausts steam; and, secondly, of increasing the revolutions of the engine, so that I am enabled to develop any predetermined power in a smaller-sized engine than has heretofore been capable of developing such predetermined power. With these ends in view I have devised the novel construction of which the following description, in connection with the accompanying drawings, is a specification, numbers being used to indicate the several parts.

Figure 1 is a side elevation of an engine, illustrating my invention as applied in connection with a slide-valve, one of the valve-chests being in vertical section; Fig. 2, a plan view of the cylinder and a portion of the bed-plate, one of the valve-chests being in horizontal section; Fig. 3, a side elevation on an enlarged scale, illustrating my invention as applied in connection with an oscillating valve, the valve-gear being identical in both constructions; Fig. 4, an enlarged detail view of the liberating mechanism; Fig. 5, a side view corresponding with Fig. 4; Fig. 6, a detail view of the counter-weight and parts operating in connection therewith; Fig. 7, a vertical longitudinal section of the cylinder, illustrating the manner in which the valves take and exhaust steam, the position of the left or inner valve

corresponding with the position of the valve-gear in Fig. 4, the piston moving toward the right, and steam having just been cut off by the left valve, the right valve being in its exhaust position; and Fig. 8 is a diagram illustrating the extremes of oscillation of the crescent arm and the parts operating in connection therewith.

1 is the bed-plate of the engine; 2, the cylinder; 3, valve-chests; 4, the crank-disk; 5, the connecting-rod; 6, the cross-head block which slides in guide-bars 7; 8, the governor; 9, the governor-lever; 10, the eccentric; 11, the eccentric-rod, and 12 a belt extending from a pulley on the crank-shaft to a pulley, 13, on a short shaft, through which rotation is imparted to the governor-shaft. All of these parts may be of the usual or any preferred construction, as the special construction thereof in no way affects the operation of my invention.

As stated above, my invention is equally adapted to sliding or oscillating valves. In Figs. 1 and 2 I have illustrated its application to an ordinary slide-valve, and in Figs. 3 and 4 to an ordinary oscillating valve. As the special construction of these valves forms no portion of my present invention, it is not deemed necessary to describe them in detail.

14 is the valve-operating shaft, which passes through the bonnet or cover 15 of the valve, and 16 is an arm, ordinarily of crescent form, and preferably journaled upon the valve-operating shaft. The crescent arms 16 are curved upwardly and toward each other, as is clearly shown, and their upper ends are connected by a link, 17. A similar link, 18, extends backward from the inner valve, and is pivoted to the lower end of eccentric-rod arm 19, the eccentric-rod being pivoted to said arm, as clearly shown in Figs. 1 and 3. As the mechanisms of the two valves are identical in construction, the singular number will be used in the description.

20 is a crab-claw pivoted to the crescent arm. The arm of the crab-claw curves downward, and is engaged by a lug or teat, 21, upon a sleeve, 22, which turns freely on the valve-operating shaft, as will be more fully explained.

23 is a liberating-latch provided with a

shoulder, 24. This latch is made integral with the crab-claw, or may be attached thereto, if preferred.

24^a is a rod pivoted to the crab-claw under 5 the liberating-latch. This rod is preferably pivoted in a recess in the crab-claw, as clearly shown in Fig. 4.

25 is a sliding block guided by rod 24^a, said block being pivoted to the upper arm of a 10 bell-crank lever, 26; which is rigidly secured to the valve operating shaft.

27 is an arm projecting downward from sleeve 22 on the valve-operating shaft.

28 is a link which connects arm 27 with the 15 lower arm of a bell-crank lever, 29, pivoted to the bed-plate, a link, 30, extending from the upper arm of this lever to governor-lever 9, which is pivoted to an arm, 31, projecting from the governor-standard. A link, 32, connects arm 27 on the operating-shaft of the inner valve to a similar arm upon the operating-shaft of the outer valve. The arm upon the outer valve, however, projects upward, instead of downward, as is of course necessary 25 in order to effect a perfect timing of the mechanism.

33 is a rod pivoted to the lower arm of bell-crank lever 26, which carries a counter-weight, 34, adapted to move within a box or casing, 35, upon the bed-plate. Rod 33 passes loosely through the weight, the latter being held on the rod by a collar, 36. The weight is provided with a central recess, 37, to receive a spring, 38, one end of the spring being adapted 35 to bear on the bottom of the recess and the other against a collar, 39, on the rod.

It will be apparent that as the lower arm of bell-crank lever 26 swings downward the rod must be carried downward against the power 40 of the spring, which acts at the completion of the downward movement to return the lever to the intermediate position in which it is shown in Fig. 3—that is, the position in which the valve is neither taking nor exhausting steam. When the upward movement of this 45 arm takes place—that is, when the upper arm of the lever swings toward the left—weight 34 is raised by the rod, and as soon as the movement is completed acts to return the 50 parts to the intermediate position again. Each movement of the eccentric-rod toward the right imparts a similar movement to the valve-links, which are pivoted to the respective crescent arms of the two valves. These arms turn 55 freely on the valve-operating shafts, and of course carry the crab-claws with them. In the present instance (see Figs. 4, 7, and 8) the parts are so arranged that the movement of the valve-links toward the right causes the 60 right or outer valve to exhaust steam and the left or inner valve to take steam, and vice versa. As shown in Fig. 3 the parts are at the intermediate position—that is, at the instant neither valve is taking nor exhausting 65 steam, the piston being at the end of its stroke toward the left. In order to cause the

left or inner valve (whose operation I will describe more fully) to exhaust, it is necessary that the crescent arm shall be moved toward the right from the position in which it is shown in Fig. 4. This movement is accomplished against the power of spring 38 until the eccentric is at that extreme of its throw, at which instant the return movement commences, being assisted by the power of the 75 spring until the parts are at the intermediate position shown in Fig. 3. An opening is provided in the bed to receive rod 33 when the crescent arm moves toward the right.

In order to cause the left valve to take steam, 80 it is necessary that the crescent arm should move toward the left. This movement, which is also accomplished by the eccentric, is against the power of the weight, which is necessarily raised by said movement until the eccentric 85 has reached the extreme of its throw in the opposite direction. The weight then acts to return the parts again to the intermediate position. So long, of course, as sliding block 25 is retained by latch 23 bell-crank lever 26 is 90 carried toward the left, and as said lever is rigidly secured to the valve-operating shaft it causes continual taking of steam by the valve. As it is desirable, however, that the valve should not take steam during the entire movement of the crescent arm toward the left, I have provided a lug or teat, 21, upon a loose sleeve, 22, on the valve-operating shaft, which, as the crab-claw moves toward the left, engages the arm and raises it, carrying the latch 100 with it, so that the sliding block is released. The instant that the block is released counter-weight 34 will draw bell-crank lever 26 and the valve-operating-shaft toward the right, thus instantly cutting off the passage of steam 105 into the valve.

In Fig. 4 I have illustrated the position of the parts at the instant that the eccentric is at the extreme of its movement toward the left, the lug or teat having already operated to release the sliding block from the latch and the valve being closed—that is, at the intermediate position referred to. As the crescent arm moves toward the right from the position shown in Fig. 4, the crab-claw is of course carried 115 with it, the curvature of the arm of the crab-claw being such that it will ride down on the opposite side of the lug or teat, and will permit the latch to engage the sliding block again, all of which is clearly illustrated in diagram, 120 Fig. 8. A spring, 40, is provided at the base of the latch, to prevent the block from coming forcibly in contact with the latch, and also to hold it in engagement with the shoulder, the block being held in engagement with the latch 125 during the exhaust—that is, during the movement of the bell-crank lever toward the right, and until it is again released by the lug or teat during the movement toward the left, these movements being continuously repeated. It 130 will of course be apparent from what has already been said that the instant at which the

cut-off takes place entirely upon the position of the teat on sleeve 22.

In order to make the cut-off automatic, I have connected the respective arms 27, which project from sleeves 22 of each valve, by a link, and have furthermore connected said arms with the governor, as has already been described. Suppose, now, that the revolutions of the engine are increasing beyond the desired speed. The effect will be to raise the inner end of governor-lever 9, which, acting through the links and bell-crank lever 29, will move arm 27 toward the left, which will carry sleeve 22 on the valve-operating shaft, upon which the lug or teat is formed, toward the right, thus reducing the speed of the engine by causing the steam to be cut off earlier in each stroke. Suppose, on the other hand, that the revolutions of the engine are decreasing from the desired speed. This will have the contrary effect. The inner end of the governor-lever will drop, which, acting through the intermediate connections, will cause the sleeve, teat, and valve-operating shaft to be moved toward the left, so that the valve-operating shaft will have a greater oscillation before the lug or teat will come in contact with the arm of the crab-claw, and cause the latch to release the block and the steam to be cut off. The engine illustrated in the drawings commences to take steam in the left valve, for example, the instant the crescent arm and valve-operating shaft move toward the left from the intermediate position in which the parts are shown in Fig. 3, the piston being at this instant at the extreme left of its stroke. The piston now begins to move toward the right, and the movement of the crescent arm, bell-crank lever 26, and the valve-operating shaft toward the left continues until the arm of the crab-claw engages the teat on sleeve 22. This acts to raise the crab-claw, which releases the block from the latch and allows the counter-weight to return the parts to the intermediate position, thus cutting off the steam instantly. The position of the valve and piston at this instant is clearly shown in Fig. 7, and the position of the valve mechanism in Fig. 4. The piston continues to move toward the right from the position shown in Fig. 7. Meanwhile the crescent arm continues to move toward the left until it reaches the extreme of its movement in that direction, as indicated in dotted lines in diagram, Fig. 8. The crescent arm now moves toward the right again, and at the intermediate position (see Figs. 3 and 8) the arm of the crab-claw will have passed over the teat, so that the latch will have dropped down and engaged the block again. At this instant the piston will have completed its stroke toward the right and will begin to move toward the left. The movement of the crescent arm toward the right continues until it reaches the extreme of its movement in that direction, as indicated by dotted lines in diagram, Fig. 8. It then moves toward the left again. While

the crescent arm has been moving from the intermediate position to the extreme position toward the right and back to the intermediate position again the piston will have been moving toward the left, the block will have been carried by the latch, and the valve will have been exhausting. The position of either of the valves in exhausting is shown at the right in Fig. 7. The piston now begins to move toward the right again, the crescent arm moves toward the left, and the valve takes steam again, the taking of steam continuing until the steam is cut off by the engagement of the arm of the crab-claw with the teat, as already described.

It will of course be understood that the details of construction may be varied within reasonable limits without departing from the spirit of my invention. I do not wish to be understood as claiming, broadly, the use, in connection with an engine, of valve-gear which permits the release of the valve before the end of the stroke in one direction and holds it rigidly to the end of the stroke in the opposite direction; but,

Having thus described my invention, I claim—

1. The valve-operating shaft, lever 26, block 25, and arm 16, having a crab-claw with latch 23 pivoted thereto, in combination with teat 21, rod 33, having collars, as shown, counter-weight 34, and spring 35, whereby the parts are held in operative position during the exhaust.

2. In an engine, the combination, with a valve, its operating-shaft and operating-lever, and a block pivoted to said lever, of an oscillating crescent arm carrying a crab-claw, pivoted rod 24^a and a latch, teat 21, spring 38, and counter-weight 34, arranged as described, and for the purpose set forth.

3. The valve-operating shaft, arm 16, journaled thereon, and crab claw 20, provided with latch 23, which is pivoted to said arm, in combination with lever 26, secured to the valve-operating shaft, and block 25, pivoted to said lever, which is engaged by the latch to cause the valve to take and exhaust steam.

4. The combination, with the valve-operating shaft, arm 16, journaled on said shaft, crab-claw 20, having latch 23 pivoted to said arm, and a rod, 24^a, pivoted in said crab-claw, of a bell-crank lever, 26, secured to the valve-operating shaft, a sliding block, 25, pivoted to said lever, which slides on said rod and is engaged by the latch, and means, substantially as described, whereby said lever is returned to an intermediate position from either extreme of its throw.

5. The valve-operating shaft having a lever, 26, secured thereto, a pivoted block carried by said lever, and sleeve 22, having teat 21, in combination with an arm, 16, journaled on said shaft, a crab-claw pivoted to said arm, which is adapted to engage the teat, and is provided with a pivoted rod, 24^a, which carries

- the block, and a latch, 23, adapted to engage said block, substantially as described.
6. The valve-operating shaft, bell-crank lever 26, block 25, and sleeve 22, having seat 21, in combination with arm 16, crab-claw 20, having latch 23, rod 33, having collars 36 and 39, and weight 34, and spring 38, operating as described, whereby the valve-operating shaft is returned to its intermediate position as soon as the block is released, and the parts are held in operative position during the exhaust.
7. The valve-operating shaft, lever 26, and block 25, in combination with arm 16, the crab-claw having latch 23, rod 24^a, and spring 40, substantially as described.

8. The valve-operating shaft, bell-crank lever 26, having block 25, and the crescent arm, and crab-claw having latch 23, in combination with rod 33, pivoted to lever 26, weight 34, having a central opening to receive spring 38, 20 and casing 35, surrounding the weight.

In testimony whereof I affix my signature in presence of two witnesses.

WILLIAM S. HALSEY.
